UNITED STATES PATENT OFFICE

FRANCIS E. ASHTON, OF CHESTER, PENNSYLVANIA, ASSIGNOR TO ABERFOYLE MANUFACTURING COMPANY, OF CHESTER, PENNSYLVANIA, A CORPORATION OF PENNSYLVANIA

LOOM

Application filed December 5, 1928. Serial No. 323,818.

This invention relates to a loom for weaving. In the standard loom which is in almost universal use today, there is a warp beam which provides the warp threads which are carried by the heddles and alternately raised and lowered to provide the required sheds into which the weft threads are woven.

The weft threads are provided by means of shuttles containing bobbins wound with weft thread and which are passed to and fro through the successive warp sheds by means of picker sticks which are operated by cam mechanisms.

These bobbins are each wound with a different colored weft and the shuttle boxes usually move vertically in order to bring the proper shuttle to a position in line with the shed of the warp.

The bobbins which are carried by the shuttles contain but a very small amount of thread and the shuttles are very carefully packed with felt or other soft material which exerts a retarding action on the thread of the bobbin and prevents it from feeding therewith in any greater quantity than desired.

These bobbins, on account of the small amount of thread which they carry, are required to be changed quite frequently so that there is great likelihood of defects in the cloth at the ends of these weft threads, while the greatest loss arises from the necessity of changing bobbins in shuttles, which requires the stopping of the loom and a consequent reduction in output.

Various devices have been recommended for eliminating the necessity of stopping the loom and, therefore, increasing the output, and among which will be found my co-pending applications, Serial No. 224,342, filed December 24, 1927, and Serial No. 250,790, filed January 31, 1928.

In both of the above mentioned cases, the shuttles and shuttle boxes have been entirely eliminated and the weft threads are selected and passed through the warp sheds by recip-

rocating means entering from each side of the warp.

In the present invention, I contemplate the use of a single shuttle or weft carrying member which receives and carries a double weft thread through the warp shed and returns it through a succeeding shed, and then releases the loop thus formed and receives another loop.

The object of this invention, therefore, is to produce a loom in which the weft thread will be continuously woven into the weft from a single supply.

Another object of the invention is to provide a loom in which the weft thread will be placed in position to be received and retained by a moving member for passage through the warp shed.

Another object is to provide a loom for automatically operating a weft carrying member to discharge and receive weft loops.

According to the invention, the lay of the machine is extended at one side to provide sufficient thread for the return of the shuttle to its initial position and each end of said lay is provided with a shuttle receiver and with a picker stick for throwing the shuttle to and fro.

The loom is provided with a needle which receives weft thread from a suitable source and places successive loops thereof in position to be received by a loop carrier in the shuttle, mechanism for brushing aside the discarded loops from the shuttle, and means for operating the loop carrier to discharge return loops from the carrier and receive new loops thereon from the needle.

The loom may also be provided with an automatic clamp which limits the amount of thread fed to the needle so that the weft threads are drawn taut in the fell of the cloth.

The drawings illustrate an embodiment of the invention and the views therein are as follows:

Figure 1 is a front elevation of a loom designed in accordance with my invention,

Figure 2 is an enlarged partial end view of my improved loom, taken from the right hand side of the view shown in Figure 1,

Figure 3 is a top plan view of the right hand side of the loom,

Figure 4 is a detail view looking in the direction of the arrow A in Figure 3,

Figure 5 is a vertical section taken on the line 5—5 of Figure 3 and looking in the direction of the arrows,

Figure 6 is a diagrammatic view showing the position of the shuttle in relation to the warp when the weft thread is being received by the shuttle,

Figure 7 is a like view with the thread and part of the fabric and warp broken out and illustrates the relation of the shuttle to the warp when the same has been advanced from its initial position,

Figure 8 is a like view showing the position of the shuttle in regard to the warp after it has been returned to its initial position and with the woven weft loop still retained therein,

Figure 9 is a detail side view of the weft thread clamp device,

Figure 10 is an exaggerated view, partly broken out, of the woven fabric with the weft loops still remaining thereon,

Figure 11 is a side view of one form of shuttle used with my improved loom,

Figure 12 is a top plan view thereof,

Figure 13 is a vertical sectional view on the line 13—13 of Figure 12,

Figure 14 is a top plan view of another form of shuttle,

Figure 15 is a longitudinal sectional view taken on the line 15—15 of Figure 14,

Figure 16 is a cross-sectional view of the entire shuttle taken on a line which may be indicated by the line 16—16 of Figure 15, and looking in the direction of the arrows,

Figure 17 is a like view on a line which may be indicated by the line 17—17 of Figure 15,

Figure 18 is a side view of the actuator for the shuttles shown in Figures 14 to 17 and shows the manner in which the same is mounted, and

Figures 19 and 20 illustrate the movement of the bell crank which brushes the released loops aside at two different positions of the lay.

The loom has a frame 21, arches 22, dobby 23, pattern cylinder 24, breast beam 26, lay 27, hand rail 28, reeds 29, heddle frames 30, swords 31, for carrying the lay and hand rail, temples 32, pulley 33, and shipper handle 34. With the single exception of the lay, these parts are arranged in the usual and customary manner and operate precisely the same as they do in the conventional loom.

The left hand end of the lay, as shown in Figure 1, is extended, as at 36, and the right

and left hand ends of the lay are provided with a shuttle receiver 38 and 39, respectively. This shuttle receiver is built onto the end of the lay and is designed to receive but one shuttle and differs from the ordinary shuttle box in that it is not vertically movable.

The loom having but a single shuttle receiver on each end of the lay, it follows that only one color of weft thread can be woven into the fabric with the loom as here shown. But the warp may contain as many colors as desired and patterns may be woven into the fabric F by means of the pattern chain 40 which controls the operation of the jacks 45.

In the case of a plain or striped fabric, the dobby, pattern cylinder, and pattern chain may be omitted and two heddle frames 30 may be operated by a cam or other mechanism for forming the successive warp sheds.

The shuttle receivers 38 and 39 are provided, respectively, with picker sticks 41 and 42 which are operated by cam mechanism, as in the conventional loom. On the right hand side of the loom is a platform 43 on which is mounted a cone box 44 which is adapted to contain a cone of weft thread, the feed-off strand of which is indicated by the letter X.

By reference to Figures 2, 3 and 4, it will be apparent that the weft thread X passes through a guide 46 mounted on the loom frame and thence passes to a horizontal guide 47 illustrated in Figures 2, 3 and 4, and mounted on the front edge of the frame.

From the guide 47, the weft thread makes a right angle turn, passes through the guide 48 on the top of the breast beam 26, and thence between the clamp discs 49 and 51 which are also positioned on the top of the breast beam and from these discs the weft thread passes through another thread guide 52 mounted on the inner edge of the upper end of the breast beam and from thence passes through the needle 53 and then to the fabric, as shown in Figures 6, 7 and 8. The needle 53 is formed

of a piece of tube and has a cut-out portion 54 for receiving the thread. This needle is fastened to the inner edge of the breast beam 26, as shown at 56 in Figure 2.

The main shaft 57 of the loom is set in motion by the operation of the shipper handle 34 and this shaft is provided at a point near its right hand end with a cam 58. This cam has a dual purpose and one is to operate the clamp discs 49 and 51 which are clearly shown in Figures 3 and 4.

An ogee crank 59 is pivotally fastened to the frame 21 at the point 61 and the upper arm 62 of this crank engages the cam 58, while the lower arm 63 has secured thereto, by any suitable means, a wire 64 which passes over a sheave 66 on the side of the frame 21 and then extends vertically, passes over another sheave 67 on the upper end of the front of the frame and in line with the breast beam 26, and is

then connected to the shaft 68 on one end of which the clamp disc 49 is mounted.

By reference to Figure 9, it will be seen that the clamp disc 51 is securely mounted in a pedestal 69 by the set screw 71, while the clutch disc 49 is mounted on the shaft 68 which is slideable in the bearing pedestal 72 and between this pedestal and the clamp disc 49 and surrounding the shaft, is a spiral 10 spring 73.

The weft thread X which is being fed from the cone box 44, will always pass between the discs 49 and 51 and when there is no tension on the wire 64 so as to compress the 15 spring 73, the said spring will press the disc 49 firmly against the disc 51 and therefore clamp the weft thread between said discs.

Let us consider that a shuttle, such as that shown in Figures 11, 12 and 13, is being used 20 for weaving the weft thread into the warp. Consider that the shuttle is in the right hand shuttle receiver 38. The cam 58 engages a follower 74, which is pivotally mounted on the frame 21, at 76. The outer end of this 25 follower is connected by a spiral spring 77 to the floor M so that the follower will at all times bear on the cam 58 intermediate the pivotal point 76 and the outer end connected with the spring 77. The inner end of the follower 74 is pivotally connected at 78 to a rod 79 which extends upward through a bearing 81, fastened to the inner side of the lay 27.

Secured to the upper end of the rod 79, by 35 suitable locking nuts, is a plate 82 which extends forward and over the lay 27, and is provided on its inner end with an actuating pin 83 which is slideable in said plate by reason of the position of the lock nuts 84 and the flange nut 86.

The actuating pin 83 is steadied in its 40 operation by means of the annular bearing plate 85 through the horizontal portion of which the said pin passes and the vertical part of which is fastened to the inner side of the lay.

The actuating pin 83 is disposed directly 45 above the center of the shuttle 87 when the same is residing in the right hand shuttle receiver 38 and clearly shown in Figure 3. The location of the actuating pin 83 in this position will force the plate 82 to be placed awry, as shown in Figures 3 and 4.

The shuttle shown in Figures 11, 12 and 13 has a longitudinal slot 88 in which a lever 89 is pivotally mounted at 91. The shuttle is provided with a transverse channel 92 which has a shoulder 93 providing an undercut transverse slot 94. The end of the lever 89 50 which extends into the transverse channel 92 terminates in a downwardly extending pin 96 whose lower end normally rests in a slight depression 97 in the bottom of the channel.

At the center of the shuttle, provision is 55 made for the housing of a spiral spring 98

which rests beneath the inner end 99 of the lever 89 and normally presses the same upward so as to force the end of the pin 96 on its other end into the slight depression 97 in the transverse channel 92.

The shuttle 87 has substantially the same configuration as the usual shuttle used in the conventional loom and is rounded off at each end and provided with the steel tips 101 backed by the fibre plate 102.

It will thus be apparent that when the cam 58 actuates the follower 74 to lower its inner end about the pivotal point 76, the rod 79 will be pulled downward and the actuating pin will be forced downward onto the top of the inner end 99 of the lever 89, thereby compressing the spiral spring 98 and raising the pin 86 from the slight depression 97 until its bottom end is substantially on a level with the bottom of the shoulder 93.

Referring now to Figures 2, 3 and 4, the breast beam is provided with a plate 103 which is fastened thereto by means of the screws 104 and the same extends over the inner edge of the breast beam, as at 106, and is provided with a post 107 on the upper end of which a bell crank 108 is pivotally mounted at 109. The outer leg 111 of the bell crank is pivotally connected to a link 112 whose other end is pivoted at 113 in the bracket 114 connected to the side of the hand rail 28.

The other arm of the bell crank is bent downward, as shown in Figures 4 and 5, until the lower flat portion 116 is just slightly above the upper surface of the breast beam 100 and the outer end of this portion 116 is arcuate and provided with serrations 117 so that, upon the discharge of the loop from the pin 96 of the shuttle 87, and the rearward motion of the lay, the serrated end of the bell crank arm will brush the said discharged loop aside and over the woven fabric.

The front heddle frame designated 118 has a vertical bar 119, square in cross-section, secured thereto and this bar operates through 110 a guide 121, fastened to the arch 22, and through the beam 122, and its lower end is connected by a spiral spring 123 to the floor M.

This bar 119 has a rod 124 which extends 115 forwardly and is provided on its end with a hook 126, while the lay 27 is recessed, as shown at 128 in Figures 3 and 5, to permit the said rod to assume its lowermost position.

The operation of my improved loom can 120 probably best be understood by first explaining the result of the operation in connection with the weaving of cloth. For this purpose, let us refer to Figures 6, 7 and 8.

In Figure 6 the shuttle is at the right hand 125 side of the warp and the needle 53 is placing a new loop of weft thread in the shuttle. Upon the operation of the picker stick, the shuttle is passed across through the warp shed to the position shown in Figure 7. The shed

is now changed and the picker stick at the left hand side of the loom passes the shuttle through the new shed to the position shown in Figure 8. The loop which is in the shuttle must now be released and a new loop from the needle placed thereon, as shown in Figure 6.

It is apparent from an inspection of the figures above mentioned that a double warp 10 strand is woven into every pick of the fabric.

To accomplish the result above described, let us assume that the lay 27 is in the position shown in Figure 2. The crank 129 moves 15 about the shaft 131 in the direction shown by the arrow and by reason of the gears 132 on said shaft and the gear 133 on the shaft 57, the shafts will rotate in opposite directions.

In the position of the lay, as shown in Figure 2, the shuttle 87 is just about to be thrown from the right hand side of the loom through the warp shed and by the time the shuttle reaches the receiver on the left hand side of the lay, the crank 129 will have made a little more than one-half of a revolution but the gears 132 and 133 are so arranged that the speed of the shaft 57 is exactly one-half the speed of the shaft 131.

Consequently, the cam 58 will during this same period move slightly more than a quarter of a revolution and the cam is so timed that at the very instant the shuttle reaches the receiver 39, the said cam will disengage the ogee crank arm 62 and the tension thus being released, the springs 73 will move the disc 49 firmly against the disc 51 and thereby clamp the thread X.

The amount of thread which has been carried by the shuttle in its movement from the right to the left hand side of the loom will be exactly that required to complete its return to the receiver 38 on the right hand side of the loom and to draw the same firmly into the selvage which is being formed on the left hand side of the fabric.

In order to complete this return of the shuttle, the lay 27 is moved forward on the swords 31 and on the return stroke and at about the position of the crank shown in Figure 2, the picker stick on the left hand side of the loom will operate and pass the shuttle back into the receiver 38. At the end of this stroke the lay will be in about the same position as shown in Figure 2, but the crank 129 will be a little more than 180° from the position shown in that figure and the cam 58 on the shaft 57 will be slightly more than 180° from the position shown.

As the lay continues to move forward by the operation of the crank 129, the cam 57 will engage the follower 74, pulling the forward end of the same downward so that the rod 79 will bring the actuating pin 83 down 65 onto the top of the inner end of the lever 89

in the shuttle 87. This will compress the spring 98 and raise the pin 96.

At this movement, the selvage heddle 118 is raised and the loop which is designated 136 in Figure 8 will pass into the hook 126 on the rod 124 and as this rod rises, the loop will be pulled from the pin 96.

As the lay has now moved to its very forward position, the needle 53 will have entered the channel 92 in the shuttle 87 and at the right of the pin 96. That part of the thread which I have designated 137 in Figure 6 will be drawn into the undercut slot 94 so that the thread will be disposed behind the slight depression 97 into which the pin extends 80 when the same is lowered.

While in this position the cam 58 ceases to hold the rod 79 down and the spring 77 on the rear of the cam follower 74 will force the rod upward and thereby disengage the actuating pin 83 from the end of the lever 89. The lay then moves to the rear and as it does so, it operates the bell crank 111 through the link 112 and the serrated arm 117 of the bell crank will pull the loop from the hook 126 90 and brush the same over onto the woven fabric F.

As the loom returns to the position shown in Figure 2, the cam 58 will have entirely disengaged the follower 74 and will engage the upper arm 62 of the ogee crank 59 and through the wire 64 will pull the shaft 68 carrying the disc 49 outward, thereby releasing the tension on the weft thread X, so that when the picker stick strikes the shuttle, the weft thread may be paid out as required.

The cam 58 for operating the clamp mechanism must be accurately timed so that it will immediately cut off the supply of weft thread when the shuttle nests in the receiver 39 at 105 the left hand side of the lay in order that the finished selvage edge on the left hand side of the fabric shall be smooth and even. The loops 136 at the right hand side of the fabric may be sheared from the material or 110 singed off so that the right hand side of the fabric will present an even finished appearance.

If desired, a shuttle such as that shown in Figures 14 to 17 inclusive and designated 141 115 may be employed. This shuttle has a recess 142 into which a body 143 of some light material, such as aluminum, is placed. The body is provided with a cut-out portion or recess 144 and a shaft 146, with its longitudinal 120 center just above the bottom portion of this cut-out, is provided on its end with a hook member 147.

The body is also provided with a recess 148 and the shaft 146 extends through this recess and is journaled on the other side thereof and on that part which extends through the recess it is provided with a pinion 149. This pinion meshes with another pinion 151 in said recess and mounted on a shaft 152 which 130

extends over the inner flat part 153 of the body and is provided with a ratchet wheel 154. The cut-out or recess 142 in the body 143 provides the equivalent of the transverse channel 92 in the shuttle 87 shown in Figures 11, 12 and 13 and is for the entrance of the needle 53 when the lay 27 is at its extreme front position.

Immediately behind the hook member 147 is a plate 156 which has a knife edge 157. The front face of each of the hooks 158 is curved, while the rear face is flat.

When this form of shuttle is used, it is necessary to remove the actuating pin 83 from the plate 82 and provide the plate 82 with a slotted end for pivotally mounting a pawl 159 at the point 161. It will also be necessary to provide a recess 162 extending back from the slotted end of the plate to house a spiral spring 163 whose tension must be exerted against the pawl 159 to hold the same in its forward position so that upon actuation of the rod 79, through the action of the cam 58 on the follower 74, the pawl will engage the ratchet 154 on the shaft 152 and by reason of the ratio of the gears 151 and 149 being 2 to 1, the hook member 147 will be rotated 90° when the pawl is lowered and the old loop 136 will be sheared by the knife 157 and the thread 137 will be caught by the succeeding hook and held in the shuttle.

In the use of this shuttle, there will in reality be no loops 136 as the loops are severed by the knife 157 but there will be just as many ends extending out from the selvage as is now shown in Figures 6, 7 and 8.

These looms are now in operation, have given great satisfaction and are producing greatly increased yardage over the conventional looms.

The loom, as here illustrated, may be modified and changed in various ways without departing from the invention herein set forth and hereafter claimed.

45 I claim:

1. A loom for use with a single shuttle, a stationary needle for feeding a loop of weft thread to said shuttle, means for holding said weft loop in said shuttle during the passage 50 of said shuttle through the warp shed and its return through a successive shed to its original position, and means to release the loop and to permit the placing of a new loop in the shuttle after each back and forth movement.

2. A loom for use with a single shuttle having a movable pin, means for feeding a loop of weft thread to said pin, means for holding said weft loop in said shuttle during the 60 passage of said shuttle through the warp shed and its return through a successive shed to its original position, and means for raising said pin to release said loop and to permit the placing of a new loop on said pin after the 65 return of the shuttle to its original position.

3. A loom for use with a single shuttle having a movable pin, a needle for feeding a loop of weft thread to said pin, means for holding said weft loop in said shuttle during the passage of said shuttle through the warp 70 shed and its return through a successive shed to its original position, and means for raising said pin to release said loop and to permit the placing of a new loop on said pin by said needle after the return of the shuttle to its 75 original position.

4. A loom for use with a single shuttle having a movable pin, means for feeding a loop of weft thread to said pin, and cam operated means for raising said pin to release said loop and to permit the placing of a new loop on said pin after the return 80 of the shuttle to its original position.

5. A loom for use with a single shuttle having a vertical movable pin, means for feeding a loop of weft thread to said pin, means for passing the shuttle to the opposite side of the loom, means for holding the weft thread when the shuttle has reached the other side of the loom and the woven weft has been beaten into the fell of the cloth, means for returning the shuttle to its original position, and means to release the said loop and to permit the placing of a new loop in said 85 shuttle.

6. A loom for use with a single shuttle having a vertical movable pin, a needle for feeding a loop of weft thread to said pin, means for passing the shuttle to the opposite side of the loom, means for holding the weft thread when the shuttle has reached the other side of the loom and the woven weft has been beaten into the fell of the cloth, means for returning the shuttle to its original position, and means to release the said loop and to 90 permit the placing of a new loop in said shuttle.

7. A loom for use with a single shuttle having a vertical movable pin, means for feeding a loop of weft thread to said pin, means for passing the shuttle to the opposite side of the loom, a clamp for holding the weft thread when the shuttle has reached the other side of the loom and the woven weft has been beaten into the fell of the cloth, means for returning the shuttle to its original position, and means to release the said loop and to permit the placing of a new loop in said 95 shuttle.

8. A loom for use with a single shuttle having a vertical movable pin, means for feeding a loop of weft thread to said pin, means for passing the shuttle to the opposite side of the loom, a cam controlled clamp for holding the weft thread when the shuttle has reached the other side of the loom and the woven weft has been beaten into the fell of the cloth, means for returning the shuttle to its 100 original position, and means to release the 105 said loop and to permit the placing of a new loop in said shuttle.

said loop and to permit the placing of a new loop in said shuttle.

9. A loom for use with a single weft shuttle, means for passing a double weft thread through the warp shed and for drawing off sufficient weft thread for passing another double strand through the succeeding shed on the return of the shuttle to its original position, means to release the loop of the woven weft from the shuttle, and to permit the placing of a new weft loop in said shuttle.

10. A loom for use with a single weft shuttle, means for passing a double weft thread through the warp shed and for drawing off sufficient weft thread for passing another double strand through the succeeding shed on the return of the shuttle to its original position, and cam operated means to release the loop of the woven weft from the shuttle, and to permit the placing of a new weft loop in said shuttle.

11. A loom for weaving with a single shuttle, comprising a lay extended at one side, a shuttle receiver at each end of the lay, a weft thread supply, means for feeding a loop of weft thread to the shuttle, and means for passing the shuttle to the receiver on the extended end of said lay whereby sufficient weft thread is drawn out to supply the succeeding pick upon the return of the shuttle to its initial receiver.

12. A loom for weaving with a single shuttle, comprising a lay extended at one side, a shuttle receiver at each end of the lay, a weft thread supply, means for feeding a loop of weft thread to the shuttle, means for passing the shuttle to the receiver on the extended end of said lay whereby sufficient weft thread is drawn out to supply the succeeding pick upon the return of the shuttle to its initial receiver, and means to release the loop of the woven weft and to permit the placing of a new loop in said shuttle.

13. A loom for weaving with a single shuttle, comprising a lay extended at one side, a shuttle receiver at each end of the lay, a weft thread supply, means for feeding a loop of weft thread to the shuttle, means for passing the shuttle to the receiver on the extended end of said lay whereby sufficient weft thread is drawn out to supply the succeeding pick upon the return of the shuttle to its initial receiver, and cam operated means to release the loop of the woven weft and to permit the placing of a new loop in said shuttle.

14. A loom for weaving with a single shuttle, comprising a lay extended at one side, a shuttle receiver at each end of the lay, a weft thread supply, means for feeding a loop of weft thread to the shuttle, means for passing the shuttle to the receiver on the extended end of said lay whereby sufficient weft thread is drawn out to supply the suc-

ceeding pick upon the return of the shuttle to its initial receiver, and means for clamping off the weft supply when the supply reaches the receiver on the extended end of the lay.

15. A loom for weaving with a single shuttle, comprising a lay extended at one side, a shuttle receiver at each end of the lay, a weft thread supply, means for feeding a loop of weft thread to the shuttle, means for passing the shuttle to the receiver on the extended end of said lay whereby sufficient weft thread is drawn out to supply the succeeding pick upon the return of the shuttle to its initial receiver, and cam controlled means for clamping off the weft supply when the shuttle reaches the receiver on the extended end of the lay.

16. A loom comprising a lay extended at one side, shuttle receivers on the ends of the lay, and means for feeding a looped weft thread to a shuttle, said shuttle being adapted on its out stroke to draw weft thread in an amount substantially equal to twice the width of the fabric to be woven.

17. A loom for weaving with a single shuttle having a vertically movable pin, a lay extended at one side, a shuttle receiver at each end of the lay, a weft thread supply, means for feeding a loop of weft thread to the shuttle pin, means for passing the shuttle through the warp shed and into the receiver on the extended end of the lay whereby sufficient weft thread is pulled out to supply the next pick when the shuttle is returned to its original receiver, means for clamping the weft supply when the shuttle reaches the extended end of the lay, and means for returning the shuttle through the succeeding warp shed.

18. A loom for weaving with a single shuttle having a vertically movable pin, a lay extended at one side, a shuttle receiver at each end of the lay, a weft thread supply, means for feeding a loop of weft thread to the shuttle pin, means for passing the shuttle through the warp shed and into the receiver on the extended end of the lay whereby sufficient weft thread is pulled out to supply the next pick when the shuttle is returned to its original receiver, means for clamping the weft supply when the shuttle reaches the extended end of the lay, means for returning the shuttle through the succeeding warp shed, and means to raise the shuttle pin to release the woven weft therefrom and to permit the placing of a new weft loop thereon.

19. In a loom, weft carrying means adapted to lay a double weft thread in a warp shed and to hold its weft and lay a double strand thereof through the succeeding shed.

20. In a loom, weft carrying means adapted to lay a double weft thread in a warp shed and to hold its weft and lay a double

strand thereof through the succeeding shed, and means to release said weft thread and permit the placing of a new loop thereof in said shuttle after the return thereof to its initial position.

5 21. A loom for use with a single weft shuttle, a stationary weft supply means permitting said shuttle to draw off on its forward passage sufficient weft thread to lay 10 another strand in the succeeding shed through which it passes on its return to its initial position.

In testimony whereof I have signed my name to this specification.

15 FRANCIS E. ASHTON.
